TEXTILE MILL SPINDLE

Herbert Gleitz, Euclid, Charles E. Miller, East Cleveland, and Jerome D. Gleitz, Euclid, Ohio, assignors to The Marquette Metal Products Company, Cleveland, Ohio, a corporation

Application April 28, 1948, Serial No. 23,656

3 Claims. (Cl. 57—130)

1

The invention relates to textile mill spindles of the type designed to be mounted in rows on the rail or frame of a spinning or twisting machine in upright position and with their bobbin-supporting blades or live spindle parts driven by a common belt or band in friction contact with whorl portions of the blades.

One problem in connection with spinning spindles is the provision of a light weight, durable and snag-proof bobbin support or upper spindle blade assembly for attachment to the live steel blade above the whorl in order to enable the assembly properly to support paper or fiber tube bobbins designed to be slipped over the live spindle and driven by friction contact between the tapered interior of the tube near its top end and a complementary tapered metal surface defining the tip portion of the blade assembly. An adapter assembly commonly includes a wooden quill, tapered similarly to the tip or driving portion of a steel blade, and extending therefrom downwardly into tight abutting contact with the acorn or hub portion of the whorl, being of somewhat undersize diameter with relation to the tip and acorn respectively at opposite ends of the quill so as normally to be out of contact with the bobbin tube. The wooden quills, largely due to shrinkage of the wood, do not remain in snug, closed joint abutment both to the whorl acorn and the driving tip, and the narrow crevices which are frequently exposed between the wood and the metal as well as slivered or rough edges of the quill catch or snag the thread and collect lint. Lint caught in a crevice or crack at the juncture of the driving tip and the quill frequently prevents the bobbin from being easily applied and doffed and tends to make the package unbalanced or eccentric on the spindle.

Light weight metal such as aluminum has been used in place of the wooden sleeve or quill type adapters, being made in one piece and usually secured rigidly and permanently to a short stub blade portion above the whorl. The driving tip portion of such one piece aluminum body is apt to become nicked and wears rapidly by repeated engagement and disengagement with the tubes. Moreover, although the aluminum body is carefully applied to the steel spindle blade in firm contact with the whorl acorn or hub, crack-like crevices frequently develop at the line of juncture of the aluminum and steel, and, even though the crevices are of microscopic width, loops of thread which sometimes fall off the package, during doffing, catch or snag in the crevices causing damage to or breakage of

2

the thread. Lint also builds up in such crevices and interferes with proper application and driving of the bobbin tubes, making them eccentric, hence unbalanced when loaded

5 10 One object hereof is to provide an improved spindle construction including a light weight metal bobbin supporting body having provision for eliminating driving tip wear as well as eliminating thread-receiving and lint-receiving narrow crevices such as mentioned above, and a simple and economical method of producing a unitary live spindle construction adapted effectively to support paper or fiber tube bobbins.

15 Other objects and features will become apparent from the following description of the preferred construction shown in the drawing, wherein:

Fig. 1 is a longitudinal assembly view showing upper and lower portions of the bobbin support 20 in central section and portions of the spindle assembly in elevation. Fig. 2 is a relatively enlarged fragmentary sectional view showing steps in the preferred method of forming the live spindle assembly.

25 Referring to Fig. 1, the top of a bolster case 1 and its mounting flange 2 are shown. The flange has a top section 3, a vertical integral arm portion 4 of which extends upwardly adjacent the bolster-bearing-supporting portion 1a of the case to serve as a mounting for the whorl retainer unit 5.

The whorl retainer may be made according to U. S. Patent Number 2,500,717 issued March 14, 1950 and comprises a body 31 rigidly attached to the arm 4 and having a spring-biased latch plunger 35 with its end normally overhanging the whorl flange 9 but removable from that position by manipulation of a releasing disc 40 rigid with the plunger.

30 35 40 45 50 55 The steel blade 6 projecting upwardly from suitable bearings in the case 1 supports the whorl 7 by being suitably made rigid with the hub or acorn portion 8 of the whorl above the band-guiding flanges 9 and 9a thereof. The blade has an approximately cylindrical reduced diameter stub portion 9 above the whorl hub. The stub is (e. g.) press-fitted or shrink-fitted into a central socket in the aluminum or other light weight metal main body 10 of the bobbin support. The lower end of the body 10 makes a smooth joint 11 with the upper end of the whorl hub, peripherally flush with a slightly tapered tube-piloting portion 12 of said hub. The lower end of the body 10 is only a few one thousandths of an inch smaller than the largest

diameter portion of the taper 12 and, as illustrated, the taper 12 terminates upwardly at the smooth joint 11 between the acorn and body 10. The slight taper 12 could be positioned somewhat farther down the relatively hard wear-resisting acorn portion of the whorl and serve the purpose explained above.

At the top end of the aluminum body 10 the same has a reduced diameter approximately cylindrical projection 14 which may have a centering socket 15 in its end. The reduced projection 14 is press or shrink fitted to a smooth surfaced steel or other hard wear resisting metal bobbin-mating sleeve 20 in tight flush-fitting engagement at 20a with a shoulder 16 on the body 10 defining the base of the projection. The projection and sleeve are finished flush with each other at the top, preferably rounded as shown.

The main outer peripheral surface 21 of the sleeve 20 is slightly tapered complementary to the adjacent inner surface of the bobbin tube T (diagrammatically shown) to be carried on and driven by the assembly 10, 20 when the live spindle is turned by its driving band. Additionally the lower end of the sleeve slightly tapers at 22 to a reduced diameter base portion 23 of the sleeve which in turn is flush with the adjacent top peripheral surface of the adapter body. The reduction in diameter by the taper 22 is preferably on the order .005" or a total reduction of .010", the drawing greatly accentuating the actual difference as in the case of the lower taper 12.

To insure that no gaps or cracks will be present at the juncture of the steel or wear-resisting metal parts 8 and 20 and the light weight and relatively soft metal of the body 10 the parts are initially made as partially illustrated in Fig. 2 viz:

The body 10 is rough formed considerably oversize in relation to the top of the whorl hub or acorn 8 and to the lower end of the sleeve 20; and at least one of each pair of axially adjacent surfaces at each joint is dished or concave, as may be done without special expense when the part or parts is or are cut off from the metal stock of which formed. For illustration, the annular lower end face 25 of the aluminum body 10 (Fig. 2) may be recessed at a very small angle (e. g. 3°) to a plane normal to the spindle axis so that, as the body 10 is shrunk or pressed onto the steel stub 9 against the (e. g.) flat top of the whorl hub, the body can seat firmly only at the peripheral top edge of the whorl hub or acorn. Any roughness or burrs inwardly from said edge on either adjacent end surface cannot prevent close abutment at said edge. Both or either of the adjacent faces of the members 8 and 10 could be slightly dished for the desired effect. The same method of construction is followed in the case of the sleeve 20 and body joint (top Fig. 2) wherein the upper annular face or shoulder 16 of the body 10 is shown slightly dished as by the cut off tool.

When the rough assembly has been completed as described above (all parts solidly joined) the excess stock of the aluminum body 10 is turned and/or ground away and the surface finished to the desired form, as approximately illustrated by Fig. 1, the aluminum surface being smoothly flush with the adjacent steel parts as shown. During a turning operation to remove the excess metal the cutting tool cold-works the metal and, at the joints, physically closes any microscopic crevices that may have existed at the abutting surfaces due to rough or inaccurate end cutting thereof or to other causes. Preferably the tapered shoulders

12 and 22 are formed on the whorl hub and sleeve 20 during final finishing of the aluminum body 10 to size as by grinding.

The internal surface of the bobbin tube T on which the thread package is wound should fit the spindle assembly described above only at the complementary tapered surface 21 of the sleeve 20. Positioning of the joint 20a between the lower end of the wear resisting sleeve 20 and the aluminum body downwardly beyond the taper therefore has the special advantage, namely that, if the joint should open up slightly in service, any lint caught thereby will not tend to prevent firm full-face seating of the bobbin tube on the bobbin-driving surface of the sleeve. The lower end of the tube T is loosely centered first by the slight smooth taper 12 as the tube is applied and finally by the relatively enlarged upper or acorn part of the whorl below the taper—the tube being a few one thousandths of an inch oversize in relation to the acorn so as never to prevent firm seating of the sleeve 20 in the tube. Since the body 10 is almost imperceptably reduced or necked down between the smooth relatively larger circular surfaces of the sleeve 20 and whorl acorn 8 there are no shoulders such as might tend to snag or hold free thread loops; and no lint or broken thread sections can accumulate on the spindle such as would tend to make application and doffing of the bobbins difficult or the bobbins eccentric on the spindle.

We claim:

1. A textile spindle blade assembly adapted to support tapered, paper-tube-type bobbins, said assembly comprising a steel blade and whorl, a light weight metal body embracing the blade and joined thereto upwardly beyond the whorl and abutting a circular upper portion of the latter, and a tapered tube-driving tip of wear resisting metal rigidly joined to the top end of the body flush therewith and of slightly larger outer diameter somewhat above its base portion than the upper end portion of the light metal body, said body being so tapered and reduced relative to the tip and adjacent whorl portion that a uniformly tapered bobbin tube snugly fitted to the driving taper of the tip is maintained during operation of the spindle out of contact with the light metal body for the entire extent of its exposed surface.
2. As an article of manufacture, a textile spindle blade assembly comprising a hard wear resisting circular metal part and an axially adjacent light weight metal circular part, said parts being rigidly joined together in tight axial abutment all around the region of abutment, one of the parts having an inwardly dished or concave end surface and the peripheral surfaces at each side of the region of abutment being flush with each other.
3. A textile spindle construction for supporting and driving a uniformly tapered paper-tube-type bobbin, said construction comprising a steel blade and whorl unit with a mainly light metal bobbin-supporting elongated body fitted thereto concentric therewith, said body having a relatively high wear resisting metal tip at its top end, the construction being characterized in that the tip has a circular peripheral tapered surface adapted to mate drivingly with the upper inner surface of the bobbin and a relatively reduced diameter portion therebelow peripherally flush with the upper laterally exposed marginal surface portion of the light weight metal body and tightly abutting a shoulder thereof all around the body to form a closed joint, whereby the bobbin is prevented from

coming into contact with said upper marginal surface portion and the joint.
